CLAIM

The ornamental design for a decorative light, as shown and described.

DESCRIPTION

FIG. 1 is a top perspective view of a decorative light design showing my new design;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an enlarged view of the selected portion "9" in FIG. 1; and,

FIG. 10 is an enlarged view of the selected portion "10" in FIG. 1.

Any shading and cross-hatching are not features of the design but are utilized to illustrate the surface contours of the decorative light design in the drawings.

The broken lines in the drawings show the boundaries of the enlarged views and form no part of the claim thereof.
